INVENTOR.

EDWARD J. STEIN

ATTORNEY.

Paul Donnelly

UNITED STATES PATENT OFFICE.

EDWARD STEIN, OF DETROIT, MICHIGAN, ASSIGNOR OF ONE-HALF TO ALFRED ETINGER, OF DETROIT, MICHIGAN.

METHOD FOR MOUNTING UPHOLSTERING.

Application filed June 15, 1925. Serial No. 37,129.

My invention relates to a method of mounting upholstering upon furniture of various kinds. Preliminarily to the placing of the upholstering on the furniture, such as the back or arm of the chair, or the like, the outline of the arm or back, as the case may be, is built from suitable material, generally wood, to provide the frame upon which the springs used in the cushion are mounted. After the springs have been mounted upon the frame, the springs are generally tied together and a suitable covering of burlap placed about the springs and secured to the frame, so that the springs are enclosed. There is then placed upon the burlap, which covers the springs, a layer of cotton batten, a layer of tow, and then a covering of velour or other finished cloth. The upholsterer building the device then proceeds to tack one edge of the velour, or covering cloth, to the frame. After this is done, the upholsterer draws the velour tightly across the springs, stretching it with his hands and nailing it in the stretched or taut position. The frame will determine the formation of the piece upholstered and frequently this formation is quite irregular, so that the upholsterer must exercise a certain amount of skill in stretching the covering cloth, so as to remove the wrinkles and make a perfectly smooth covering over the springs and backing. In addition to requiring considerable skill of the upholsterer, the operation is one which takes considerable time, and on account of the method of securing the covering cloth to the frame, it is practically impossible to produce two pieces of upholstered furniture which are identical.

If the upholsterer is to upholster the back of a chair, the back is built integral with the rest of the chair and the upholstering done on the back, while forming a part of the chair.

With my method of securing the upholstering to a frame, whether it be a back, an arm, or another part of the furniture, the piece upholstered may be made separate from the piece of furniture with which it is to be used, so that, after it is upholstered, it may be mounted upon the piece of furniture, thus affording a detachable upholstered back, or arm.

It is an object of the present invention

to provide a method of mounting upholstering upon a frame, which will reduce considerably the labor necessary for mounting the upholstering on the frame and which will also permit of the forming of a number of pieces of upholstering, substantially identical, so that the upholstered pieces may be mounted upon pieces of furniture with which they are intended to be used, after the upholstering is mounted, so that there is arrived at a system of production in which the upholstering may be quickly and easily proceeded with, without requiring the upholsterer to handle the large and bulky piece of furniture with which the upholstered portion is to be used.

Another object of the invention is the provision of a method of mounting upholstering on a frame which consists in placing the padding and covering cloth over a form, and pressing the frame into the form, so as to retain the covering cloth in tightened position, to permit a quick and easy attachment of the covering cloth to the frame.

Other objects will appear hereinafter.

The invention consists in the combinations and arrangements of parts hereinafter described and claimed.

The invention will be best understood from a reference to the accompanying drawings, which form a part of this specification and in which

Fig. 1 is a fragmentary top plan view of the form used in the invention,

Fig. 2 is a longitudinal, central, sectional view of the form used in the invention, showing the packing and covering cloth in position preliminary to the placing of the frame in the form,

Fig. 3 is a view similar to Fig. 1, showing the frame in position preliminarily to being pressed into its final position,

Fig. 4 is a sectional view similar to Figs. 2 and 3, showing the frame pressed into its final position,

Fig. 5 is a sectional view of the frame ready for positioning in the form,

Fig. 6 is a fragmentary side elevational view, illustrating the clamping means used in the invention,

Fig. 7 is a fragmentary sectional view taken on substantially line 7—7 of Fig. 6.

In the drawings, I have shown a device,

adapted for carrying out my invention, but, as the description proceeds, it will be evident that various modifications of this form may be made, without departing from the spirit 5 of the invention, and it is my intention to embrace, within the scope of the claims attached hereto, such variations and modifications.

As shown in the drawings, there is provided a table, or supporting surface, 9, upon which is mounted a mold or form frame 10, having a form 11 formed therein. The form 11 will, of course, correspond to the frame adapted to be used therewith so that, 15 on different designs of furniture, different forms will be necessary. These forms may be formed in the frame 10, which may consist simply of a block of wood, carved out to provide the necessary cavity, or it may 20 consist of some plastic material molded to provide the desired form. Bolts 12 provided with wing nuts 13 serve to secure the frame 10 to the table, or supporting surface 9. Formed in the faces of the frame 11 25 are grooves 14. Mounted upon the frame, at intervals, are brackets 15, in which is mounted a horizontally extending shaft 16, upon which is mounted a locking strip 17 having angularly turned ends 18, adapted to 30 project into the groove 14, a spring 19 serving to normally press the angularly turned end or tongue 18 into the groove 14. As shown in Fig. 6, the strip is one continuous piece extending the full width of the frame 35 10, although a plurality of arms may be provided instead. After the proper frame 10 has been selected and mounted upon the supporting surface 9 in proper position, the covering fabric 24, which may be velour, or 40 other suitable material, is placed over the form 11 and its edges turned downwardly, so as to project beyond the groove 14, this covering fabric 24 being spaced slightly from the base of the form 11, as shown in 45 Fig. 2, the locking strip being first sprung back. The locking strip is then released so as to cause the inwardly projecting engaging members or tongues 18 to force the covering fabric 24 into the grooves 14. 50 There is then placed by the upholsterer upon the covering fabric 24 a suitable layer 25 of cotton or other desirable packing. Upon this layer of cotton 24 is then placed a suitable layer of padding such as tow 26, the 55 amount of padding being determined by the upholsterer. The frame 27, which determines the outline of the upholstered piece and to which the shape of the form 11 corresponds, is generally made from wood, and has 60 secured thereto metallic strips 28 to which one end of the springs 29 is fastened. The opposite ends of the springs 29 are joined together in any suitable manner and the frame is then covered with a layer of bur-

lap 30, so that the springs, while attached 65 to the frame 27, are enclosed. With frames constructed in the manner described, there is generally provided, at one side, a projecting portion 27', which forms the base 70 of the frame, and serves to connect the lower ends of the upwardly projecting end pieces. This frame, with the springs enclosed in the manner indicated, is then placed upon the packing, as shown in Fig. 75 3. A suitable ram 32, operated in any desirable manner, is then brought into engagement with the back of the frame 27 and serves to force the frame into the form 11, so as to stretch tautly the covering fabric 80 24. When this is done, the edges of the fabric are released by the engaging members and these edges securely tacked to the frame, while the ram 28 is pressing the frame into the form. The structure of the machine operating the ram is not described, 85 as the same forms no part of this invention, and may be any desired conventional type of pressing machine.

When the ram 28 presses the frame into the mold, the covering fabric 24 is stretched 90 uniformly throughout its area, and is held in this stretched condition, while the upholsterer is tacking its edges to the frame. It is thus seen that the operation of securing the upholstering to the frame is one 95 which may be quickly and easily done, with a considerable saving in time, and with a uniform stretching of the covering cloth throughout its entire area. The result is 100 also a more attractive product, more finished in its appearance, and displaying a degree of careful workmanship. The projecting portion 27' serves to engage against the frame 10 at the portion 27" which is formed to lie in a single plane, vertical to the base, 105 thus limiting the movement of the frame beyond a desired distance and preventing a stretching of the covering so tightly as to compress the springs. This formation also 110 serves to properly seat the frame in the mold.

A saving of covering fabric is also effected through this method, inasmuch as the fabric may be cut into pieces which are the desired size and shape, so that, when placed over the frame 10, the upholsterer may fold the edges over sufficiently to clear the grooves 115 14 before a clamping. In this manner, the upholsterer will be able to produce a number of upholstered pieces, substantially the 120 same, inasmuch as the stretching of the covering fabric 24 will be uniform in the various pieces.

What I claim is:

A device of the class described comprising, a mold bearing frame having one of the end walls of greater height than the other; an upholstery bearing frame adapted for

pressing into said mold; a projection on one end of said upholstery bearing frame adapted for engaging the inner surface of the shorter of the end walls of said mold bearing frame, the opposite end of said upholstery bearing frame engaging the inner surface of the deeper of said side walls of

said mold bearing frame and lying with its upper surface flush with the upper surface of said side wall.

10

In testimony whereof, I have signed the foregoing specification.

EDWARD STEIN.
